his ATTORNEY

UNITED STATES PATENT OFFICE.

FREDERICK JAMES MITCHELL, OF NEW YORK, N. Y., ASSIGNOR TO ALBERT L. COHN, OF SAME PLACE.

ATOMIZER.

SPECIFICATION forming part of Letters Patent No. 371,615, dated October 18, 1887.

Application filed January 22, 1887. Serial No. 225,222. (No model.)

To all whom it may concern:

Be it known that I, FREDERICK JAMES MITCHELL, a subject of the Queen of Great Britain, and a resident of New York city, in the county of New York and State of New York, have invented certain new and useful improvements in apparatus for operating an atomizer automatically from a distance by the opening and closing of a door or other movable thing, as hereinafter more fully explained, of which the following is a specification.

My invention relates to improvements in such apparatuses as above mentioned, in which the disinfecting, deodorizing, or perfuming is accomplished by atomizing the disinfectant, deodorizer, antiseptic, or perfume into the room or place to be disinfected, deodorized, or perfumed; and the objects of my improvements are, first, to provide a means for atomizing the substance, powder, or liquid into the place, and affording facilities for atomizing by the use of force or power originating at any distance desirable from the place to be deodorized or perfumed; second, to do both these things in a cheaper, better, and more lasting way than heretofore, and by means which will not easily get out of repair; third, to keep the powder, substance, or liquid of a uniform strength. I attain these objects by the mechanism illustrated in the accompanying drawings, in which—

Figure 1 is a view of the entire apparatus, showing the vessel containing liquid to be atomized and its adjuncts and the cylinder of the air forcing or compressing device in section, the air forcing or compressing device being attached to and operated by a door. Fig. 2 is a perspective view of the disk and pipes of the atomizer.

Similar letters refer to similar parts throughout the several views.

In the place to be disinfected, deodorized, or perfumed I place or attach the vessel *a*, containing the liquid disinfectant or perfume to be atomized into the room. The pipe *b* of the atomizer has its one end immersed in the liquid and the other end in close proximity to the end of the air pipe *c* of the atomizer.

The pipe *c* is by a pipe or tube, *C*, (preferably a rubber tube,) connected with an air

forcing or compressing device attached to or connected with a door or other movable object. In the drawings the device for forcing air through the pipe or tube *C* is a cylinder, *A*, which rests on two brackets, *o o*, attached to the casing of the door, which brackets are provided with pivots *p p*, on which the cylinder can turn. Piston *B* is connected with the door itself by the bracket *r*, and moves on the pivot *s*, running through the piston near its end, and the pivot *s* is held in place and moves in the projections *t t* of the bracket *r*. The piston is also provided with the section *u*, which forces air out of the cylinder *A* through the pipe *v*, to which the air-tube *C* is attached. When the piston is drawn out of the cylinder by the action of the door, it sucks air into the cylinder through the pipe *c* or *v*, and when the door is closed the piston forces the air out through the same pipe, *v* or *c*, and so atomizes the liquid in the vessel *a* into the circumambient air. I also use the disk *d*, having a slot or cut, *e*, which disk prevents evaporation, and the slot, together with the funnel *f*, allows the liquid which is drawn out and not atomized to flow down into the vessel *a* again. The disk performs the very important office of keeping the liquid at a uniform strength by not allowing too much evaporation to weaken it. This evaporation and consequent weakening has been a great defect with other devices for disinfecting and perfuming where the whole surface of the liquid has been exposed to the air.

The funnel *f* has a flange, *m*, and by means of the removable screw *w*, I screw the flange of the funnel down onto the disk *e*, thus keeping the flange tightly in place, and also pressing the disk down closely to prevent evaporation from the vessel. This screw works in the screw-thread in the neck *g* of the vessel *a*. The screw is made short enough so that its upper end will be below the opening *n* of the funnel. I prefer to use this screw instead of making the screw a part of the funnel itself, so that the hole *n* is always on the side nearest the tube *C*, which is more convenient, and which I could not depend upon if I were to screw down the funnel tightly by a screw which were part of itself.

I prefer to solder the disk *d* and the pipes *c* and *b* together. I put them in place by tak-

ing hold of the funnel and the screw, which rests on the flange of the funnel, in one hand, and with the other hand I run the straight end of pipe *c* perpendicularly up the funnel, and 5 when the end *h* of pipe *c* gets near the opening *n* of the funnel I turn that pipe horizontally and run the end *h* through that opening. Then, holding the funnel and pipes in that position, I immerse the pipe *b* into the liquid, while at 10 the same time I place the funnel within the neck *g* of the vessel *a*, and as the disk is soldered to the two pipes *b* and *c* the disk rests in place by so immersing pipe *b*. Then I screw the funnel and disk both down tightly by the 15 screw *w*.

In the accompanying drawings I show only one way of accomplishing the objects of my improvements; but I also claim all substantially similar ways which would be necessitated 20 by a different motive power than a near door. Different atomizers or different air forcing or compressing devices might be also used without departing from my invention, as the substance of my invention is having an air forcing 25 or compressing device attached to some movable object, and by means of a pipe or tube connected with an atomizer operating on liquid to atomize it into any place to be disinfected or perfumed, and even if the place into which 30 the disinfectant, antiseptic, deodorizer, or perfume is to be atomized is at a great distance from the movable object; so that if in the house or neighborhood any door or other movable thing (whether on the same floor or on a 35 lower or higher floor) is specially adapted, from its frequent use, to be connected with the

atomizer, its motion can be utilized for my improvement.

Prior to this invention I was accustomed to operate perfuming and disinfecting devices at 40 a slight distance by the use of wires over pulleys; but these wires lose some force over each pulley on which they are strung, so that they cannot be made to operate when stretched at some longer distance from the place to be operated upon, as they require so many pulleys that they are unreliable, and, in fact, can only be used for very short distances. Besides, the tension is likely to get them out of order. This is not the case with my improvement, as my 45 improvement, being pneumatic, simply employs air as the means to operate with.

What I claim as my invention, and desire to secure by Letters Patent, is—

1. An air forcing or compressing device connected with and operated automatically by a door, and by means of a pipe or tube connected with an atomizer in a suitable vessel containing liquid substance or powder to be atomized, substantially as described. 55

2. A vessel, *a*, containing disinfectant, perfume, or the like to be atomized, having a slotted disk, *d*, and funnel *f*, substantially as and for the purpose described. 60

Signed at New York city, in the county of 65 New York and State of New York, this 20th day of January, A. D. 1887.

FREDERICK JAMES MITCHELL.
